UNITED STATES PATENT OFFICE

100,126

DESIGN FOR A GLASS FOOD CONTAINER OR SIMILAR ARTICLE

Lewis H. Scurlock, Chicago, Ill.

Application March 14, 1936, Serial No. 61,631

Term of patent 14 years

To all whom it may concern:

Be it known that I, Lewis H. Scurlock, a citizen of the United States and a resident of Chicago, in the county of Cook and State of Illinois, have invented a new, original, and ornamental Design for a Glass Food Container or Similar Article, of which the following is a specification, reference being had to the accompanying drawing forming a part thereof:

Fig. 1 is a top plan view of a glass food container or similar article showing my new design.

Fig. 2 is a side elevation of said container.

Fig. 3 is an end elevation of said container.

Fig. 4 is a vertical section through one end wall of the container.

The dominant feature of my design resides in the configuration of the rim portion of the container at the upper edges of the vertical end and side walls, as shown.

I claim:

The ornamental design for a glass food container or similar article, as shown and described.

LEWIS H. SCURLOCK.
